UNITED STATES PATENT OFFICE.

GEORGE H. FORSYTH, OF CHICAGO, ILLINOIS.

DISK WHEEL.

1,373,185.

Specification of Letters Patent. Patented Mar. 29, 1921.

Application filed September 29, 1919. Serial No. 327,108.

To all whom it may concern:

Be it known that I, GEORGE H. FORSYTH, a citizen of the United States, residing at Chicago, in the county of Cook and State of Illinois, have invented certain new and useful Improvements in Disk Wheels, of which the following is a specification.

By reason of the growing scarcity of materials suitable for employment in the making of wood wheels and the rapid deterioration of same under stress of weather and liability to damage by rough usage, they are coming into disfavor; the wire wheel has many objectionable features inherent in manufacture and employment; the steel wheel of spoke or "artillery" type, while desirable from many points of view, is very expensive to manufacture; and current types of steel disk wheels, if sufficiently strong, are heavy, unsightly, and lacking in resiliency or springiness.

The steel disk wheel is recognized as the type most cheaply constructed but it has not met with favor for other than heavy work such as on trucks and the like, being undesirable on pleasure cars for the reasons briefly indicated above. These wheels have, in general, embodied two disks spaced apart more widely at the center and approaching each other peripherally at the point of attachment to the rim. This emphasizes optimally the impression of heaviness and also sacrifices resiliency to strength, while at the same time failing to impart strength in the highest degree except as measured by capacity to carry dead loads as distinguished from resistance to laterally applied stresses resulting from skidding, striking of curbs, etc.

It has been proposed to form disk wheels of a single steel disk but, in order to reinforce the same against lateral stresses, it has been considered necessary to make the same of metal of a heavy gage, thus adding unduly to the clumsiness and weight of the wheel without securing the necessary strength at the points where most needed.

The primary objects of the present invention are to so redesign the steel disk wheel as to retain and even to reduce the recognized low cost of production, to increase its actual strength under stresses of use and to give to the same a spring resistance to reduce the actual weight, and all while at the same time retaining an appearance of light-

ness and symmetry compatible with the best pleasure cars.

According to my invention, a wheel is constructed which is adapted either to a fixed or demountable rim, the disk portion 60 of the wheel is of thin gage metal provided, advantageously, with radially extending ribs on the inner face thereof, the ribs preferably being of decreasing sectional area toward the periphery and the disk itself of 65 decreasing thickness toward the periphery whereby the disk has the greatest strength adjacent the hub portion of the wheel where most needed; the peripheral portion of the disk, ribbed or not, in some cases flanged 70 laterally to underlie and support the rim either directly or through an interposed felly member which is underlain by the flanged portion of the disk and has a shouldered portion against which the edge of the 75 disk abuts.

Other features of construction characterizing the invention will be made clear from an inspection of the accompanying drawings and a study of the following detailed description based thereon wherein are set forth several embodiments of the invention. It will be readily appreciated, however, that the description and drawings are illustrative only and are not to be taken in an un- 85 necessarily limiting sense.

In the drawings—

Figure 1 is a side elevation of the portion of the wheel illustrated in section in Fig. 3;

Fig. 2 is a similar view of the wheel 90 shown in section in Fig. 4;

Fig. 3 is a fragmentary section on the line 3—3 of Fig. 1;

Fig. 4 is a section on the line 4—4 of 95 Fig. 2;

Fig. 5 is a fragmentary section of the peripheral portion of a wheel showing the mounting of the rim; and

Fig. 6 is a similar section of a modified construction in which a removable felly 100 member is interposed between the disk and rim.

Having reference to the drawings, the central or hub portion is indicated generally at 11, the medial or disk portion at 12 and 105 the peripheral or rim portion at 13, while the brake drum is represented at 14. In Figs. 1, 2, 3, 4, and 6 the disk 12 is shown as being of substantially equal thickness throughout its radial extent while in Fig. 110

5 it is shown as of greater thickness toward the hub portion gradually decreasing in thickness toward the periphery. In each of the figures the disk is shown as provided 5 with integral radial ribs 15 of greater sectional area toward the hub portion and gradually decreasing in dimensions toward the periphery.

In Figs. 1 and 3 the peripheral portion of 10 the disk 12 is shown as seated within a recess formed around the inner margin of the felly member 16, the latter underlying the rim on the rear face of the wheel and provided with a marginal shoulder 17 with 15 which engages the extreme edge of rim supporting member 18, which member 18 is securely assembled with the disk 12 and the felly member 16 by means of a series of bolts 19 passing therethrough and also serving 20 to hold in firm association therewith the rim retaining wedge members 20 which are preferably countersunk into the outer face of the felly member 16 to afford a flush finish therewith. The rim supporting member 25 18, which preferably rests upon the ledge 18^a, bears against the shoulder 17 under pressure tending to force the felly member 16 outwardly and against the rim 13 to support the latter, as the bolts 19 are tightened.

30 In Figs. 2 and 4 a felly member 21 is shown of somewhat different configuration but similarly provided with an inwardly opening annular recess 22 within which is seated the outer edge of the disk 12. The 35 rim supporting member 18 is assembled with the felly member and with the disk in a similar manner to that previously described with the difference that a projecting lip 18^b is provided for support within a hole in the disk. The lip 18^b is preferably cupped at 40 its base to afford a spring-lock connection with the bolt 19. It will be noted that the lip 18^b extends inwardly thereby preventing undue forcing of the wedge member 23. Instead 45 of the rim retaining wedge members 20 of the former construction arranged at intervals about the periphery of the wheel, an integral rim retaining ring 23 is shown as secured in assembled relation with the rim, felly member and felly supporting member by means of the bolts 19 as before described.

Moreover, as illustrated in Fig. 4, there is secured an interlocking relation of the disk 50 and supporting members by the projection of the threaded portions of the latter into perforations of the former.

It will be noted that between the felly members and the rim in Figs. 3, 4 and 6, and between the flanged periphery of the disk and the rim in Fig. 5, there is a relative inclination which under the tightening of the rim-retaining bolts causes compression from the margin of the wheel inwardly with 65 a corresponding outward spring thrust.

The effect is to produce a disk wheel in which the assembled parts shall be in spring relation with each other and securely locked together. The outer margin of the rim supporting members are formed upwardly to 70 primarily serve as abutment members.

The supporting members 18 may consist of rings or segmental rim supporting or retaining members. In the latter case they are preferably provided with side walls to prevent 75 the entrance of dirt and moisture entering between them and the felly members 16 and 21. It is to be noted that the retaining wedge members 20 and 23 are provided with inclined surfaces 20^a and 23^a with which engage adjacent inclined surfaces of the rim felly members 16 and 21.

As illustrated in Fig. 5, there is no independent felly member but the disk 12 is inwardly flanged laterally as indicated at 12^a 80 so as to provide an integral felly to underlie the rim 13 and to serve as a support therefor, the said flanged portion of the rim being arranged at a slight inclination and provided marginally with a rim retaining 85 flange 12^b. The rib 15 formed on the rear face of the disk 12 is also continued outwardly along the rear face of the flanged portion 12^a of the disk as indicated at 15^a thus substantially reinforcing the rim supporting portion of the disk. Herein the disk is shouldered as indicated at 24 to form a suitable seat for the lower edge 25 of the rim retaining wedge members 26 held in associated relation with the rim and disk by 90 means of the bolts 27.

In Fig. 6, a felly member 28 is employed beneath the rim 13 and supported from within by means of the flanged portion 12^c of the disk 12, the extreme edge of which 105 abuts against the shoulder 29 of the felly member 28, the space above the shoulder 24 serving to accommodate not only the arm 25 of the rim retaining wedge member but also the outer edge of the felly member. Before 110 assembly of the wheel the disk adjacent to its outer edge is of slightly greater outside diameter than the inside diameter of the felly member, whereby the parts are assembled under spring stress, the latter being 115 augmented owing to the outer margin of the disk being flanged outwardly at a more gradual bend than the adjacent curve of the felly member.

In Figs. 3 and 4 are shown the details of 120 construction of the hub member and also, in Fig. 3, the assembly relation of the hub and disk with the drum. The hub is of pressed steel formation, hollow, the inner portion flanged outwardly as indicated at 30, and 125 may also be radially fluted or castellated to provide outwardly opening radial sockets to overlie the inner ends of the ribs 15. Those portions of the fluted flange 30 lying intermediate the ribs 15 bear directly upon the 130

rear face of the disk 12 between the ribs 15, and the disk 12 is securely clamped between the flange 30 and the hub ring 31 by means of the bolts 32. The wheel is thereby 5 greatly strengthened in that the angular stresses between the hub and the disk are borne in large measure by the flutings of the hub and the danger of shearing the bolts 32 is thereby eliminated.

10 Having particular reference to Fig. 3, the brake drum has its side wall at 33 radially fluted to accommodate the ribs 15 of the disk, and its inner portion surrounding the hub 11 is preferably escalloped to enter into 15 the spaces between the flutings of the hub. As clearly seen in Fig. 3, the inner margin of the wall 33 of the brake drum is securely clamped between the flange 30 and the disk 12 by means of the bolts 32.

20 I claim:

1. In a vehicle wheel, the combination with the hub and rim portions, of an intermediate disk portion having a substantially plain front face and a radially ribbed rear 25 face.

2. In a vehicle wheel, the combination with the hub and rim portions, of an intermediate disk portion having a substantially plain concave front face and a radially 30 ribbed convex rear face.

3. In a vehicle wheel, the combination with the hub and rim portions, of an intermediate sheet metal disk portion having a substantially plain front face and a radially 35 ribbed rear face.

4. In a vehicle wheel, the combination with the hub and rim portions, of an intermediate sheet steel disk portion having a substantially plain concave front face and a 40 convex rear face provided with substantially straight radial ribs.

5. In a vehicle wheel, the combination with the hub and rim portions, of an intermediate disk portion having a radially 45 ribbed rear face, said disk of gradually decreasing thickness toward its periphery.

6. In a vehicle wheel, the combination with the hub and rim portions, of an intermediate disk portion having a radially 50 ribbed rear face, said ribs of decreasing sectional dimensions toward the periphery of the disk.

7. In a vehicle wheel, the combination with the hub and rim portions, of an intermediate disk portion having a substantially 55 plain front face and a radially ribbed rear face, said disk and ribs gradually decreasing in cross sectional dimensions toward the wheel periphery.

60 8. In a vehicle wheel, the combination with the hub and rim portions, of an intermediate disk portion having a substantially

plain front face and a radially ribbed rear face, said ribbed disk at its periphery flanged laterally to form an inner support 65 for the rim.

9. In a vehicle wheel, the combination with the hub and demountable rim portions, of an intermediate disk portion having a substantially plain front face and a radially 70 ribbed rear face, a felly member underlying the rim at one side, detachable rim-retaining wedge members at the other side, the ribbed disk flanged laterally beneath the felly member to form an inner support therefor. 75

10. In a vehicle wheel, the combination with the hub and demountable rim portions, of an intermediate disk portion having a substantially plain front face and a radially 80 ribbed rear face, a felly member underlying the rim at one side and provided with an inner shoulder, detachable rim-retaining means at the other side, the ribbed disk flanged laterally beneath the felly member and bearing with its edge against the 85 shoulder.

11. In a wheel, the combination with a wheel body having radially extending rib-like members, of a hub disposed axially of the wheel body and outwardly flanged to 90 bear against the ribbed face of the wheel, the flange radially fluted to interlock with the rib-like members of the wheel, and means to clamp the hub flange to the wheel body.

12. In a wheel, the combination with a 95 wheel body having radially extending rib-like members on its rear face, of a hub disposed axially of the wheel body and outwardly flanged at its rear end to bear against the ribbed rear face of the wheel, the flange 100 radially fluted to interlock with the rib-like members of the wheel, and means to clamp the hub flange to the wheel body.

13. In a wheel, the combination with a wheel body having radially extending rib-like members on its rear face, of a hub disposed axially of the wheel body and outwardly flanged at its rear end to bear against the rear face of the wheel, the flange radially fluted to interlock with the rib-like 105 members of the wheel, a brake drum having a correspondingly fluted side wall with its fluted hub flange and ribs, and means to clamp the hub flange and drum to the wheel 110 body. 115

In witness whereof I have hereunto signed my name in the presence of two subscribing witnesses.
